UNITED STATES PATENT OFFICE.

JOHN R. HINMAN, OF INDIANAPOLIS, INDIANA.

CHAIR.

1,164,520.

Specification of Letters Patent. Patented Dec. 14, 1915.

Application filed July 24, 1913. Serial No. 730,881.

To all whom it may concern:

Be it known that I, JOHN R. HINMAN, a citizen of the United States, residing at Indianapolis, Marion county, and State of Indiana, have invented and discovered certain new and useful Improvements in Chairs, of which the following is a specification.

My invention relates to chairs and its object is to provide an opera chair having means for rigidly holding the folding seat against lateral displacement and having means to enable the chair to be adjusted to floors of different slopes.

With these objects and others in view my invention is embodied in preferable form in the article hereinafter described.

The invention is illustrated in the accompanying drawings in which—

Figure 1 is a front view in elevation of the chair; Fig. 2, a vertical section, showing the seat down; Fig. 3, a vertical section showing the side folded up; Fig. 4, a section on the line 4—4 of Fig. 2; Fig. 5, a section on the line 5—5 of Fig. 3; Fig. 6, a detail of slot and pin connection for seat; Fig. 7, a section on the line 7—7 of Fig. 2; and Fig. 8, a section on line 8—8 of Fig. 3.

Referring to the drawings, the body of the chair is preferably made entirely of metal, the side frames 1 having vertical strengthening flanges 2 and arm members 4 and being joined to a back member 5, all these parts being either formed from a single piece or welded together to form an integral body. A horizontal front brace 6 connects the two side frames, and a rear brace 3 also connects said side members and serves as a foot-rest.

A seat 7 suitably pivoted in the frame is provided and this seat is also preferably of metal.

Secured to the bottom of the seat 7 on each side thereof is a plate 8 provided with an ear 9 having an aperture 10. In this aperture fits a pivot pin 11 which is carried at the upper end of a pivoted supporting arm 12. The lower end of this arm is pivoted to a vertically sliding block 13 which is movable in and guided by the walls of a groove formed by flanges 14 of a bar 15 suitably secured to the side frame of the chair and by means of which flanges the block is held against lateral escape and insured a vertical movement in a straight line. The plate 8 is also provided with an ear 16

which is provided with a key-hole slot 17 which is adapted to engage a correspondingly shaped pin 18 projecting from the side of the chair frame. The pin 18 in the tongue portion thereof is provided with a slot 19 with which engages the wall of the slot 17, whereby after the pin has been inserted in the slot, the plate and pin may be turned relatively to one another to permit of the swinging movement of the seat, while at the same time the tongue prevents the lateral disengagement of the plate and pin during such relative movement.

Each side frame of the chair is connected near its rear edge by a bolt 20 to a base plate 21 having a horizontal supporting flange 22. Near its front edge each frame is provided with a vertical row of apertures 23, through which and a single hole in the frame is passed a locking bolt or screw 24. By means of this vertical row of holes and the removable bolt, the front ends of the frames may be adjusted up or down, swinging on the bolt 20 as a pivot, so as to thereby enable the chair to be adjusted to floors of different slopes.

The arms 12 and the pivot pins 18 constitute the sole supporting means for the seat and owing to this fact two arms are provided, one on each side and means are also provided for receiving and supporting such arms which will not yield in a plane parallel to the swinging movement of the seat but will afford a rigid support in such plane for the seat when the same is occupied. These means consist of the rigid side frames extending forwardly from the back of the seat and bolted to the base member and these side frames also constitute means whereby the guide flanges in which the blocks move may be made of strong sheet steel and welded to such supporting side frames. In assembling the chair the slot 17 in the plate 8 carried by the seat 7 is slipped over the end of the pin 18 until the wall of the slot engages in the circumferential groove or slot 19 on the pin, whereupon the seat will be held firmly against lateral escape at each end while at the same time the plate is permitted to turn freely around the pin. In raising the seat the block 13 will be carried up and down in the guideway formed by the flanges 14.

To adjust the chair to different inclinations, the side frames are swung up or down on the pivot 20 and adjustably fixed in posi-

tion by means of the front bolts 24. The pivotal adjustment thus provided permits of the adjustment of the chair to different inclinations of floors without changing the 5 distance of the rear part of the seat from the floor.

Having thus described my invention, what I claim is:

- 10 1. A seating device adjustable to accommodate the seat thereof to floors of different inclinations and comprising a rigid frame having a back and side members extending forwardly from said back, a base member having means of fixed connection to and rigid bearing on the floor adapted to engage with and laterally brace said members, means of pivotal connection between said side members and base member at their rear ends permitting an adjusting swinging 15 movement in an arc of a circle in a vertical plane of said frame with respect to said base member, means at the front ends of said side and base members for locking said parts together in the position to which they may be 20 adjusted, and a seat carried by said frame so mounted as to be movable therewith to change the angle of the seat to the floor as the frame is adjusted.
- 25 2. A seating device having a rigid frame including a back and side members extending forwardly from the back in combination with rigid base members fixed to the floor and extending from the back forwardly parallel to the respective side members for laterally bracing the same, a horizontal pivot member connecting each side member and a base member at the rear end of the latter and permitting an adjusting swinging movement of the frame on said pivot through a vertical plane, a seat carried by 30 and movable with said frame in its angular adjustment relatively to the base members, means at the front end of the base members upon which the side members of the frame bear for support, and means for locking the 35 said supporting means rigidly to the base in different positions of adjustment in said 40 swinging movement of the frame.

In witness whereof, I have hereunto set my hand and seal at Indianapolis, Indiana, 50 this eighteenth day of July, A. D. nineteen hundred and thirteen.

JOHN R. HINMAN. [L. S.]
